UNITED STATES PATENT OFFICE.

CLINTON H. HANSON, OF CHICAGO, ILLINOIS, ASSIGNOR TO THE MOTOR PLAYER CORPORATION, OF CHICAGO, ILLINOIS, A CORPORATION OF ILLINOIS.

EXPRESSION DEVICE.

Application filed February 15, 1922. Serial No. 536,678.

This invention relates to automatic musical instruments and is more specifically concerned with improvements in a device shown and described in Patent No. 1,231,809, issued 5 July 3, 1917, to Alfred Swensen.

Briefly, this device comprises two chambers, one being in communication with the atmosphere, the other with an air pump, and two ports each affording communication 10 between the chambers; there being a yieldable valve for one port actuated by the air pressure on the valve, and a positively acting valve for the other port. These positively acting valves are adapted to be controlled by 15 holes in a tracker, which are arranged to be uncovered by the note sheet. In operating an instrument according to the above patent, it has been found that the yieldable valve has a tendency to flutter and vibrate which 20 produces a slight noise and results in operating too slowly for effective results in music reproduction. Furthermore, the yieldable valve resists the passage of air momentarily and then opens suddenly with a peculiar 25 noise which is detrimental to the satisfactory operation of the instrument.

One of the objects of my invention therefore, is the construction of a yieldable valve for use in such a pneumatic device which 30 eliminates this objectionable noise and which permits the valves to respond quickly in accordance with the opening and closing of the positively acting valves. Another object is the provision of such a valve construction 35 that the closing springs for a series of them, operable under different pressures, may all be of uniform size and material. A further specific object is the provision of an adjusting device for varying tension or pressure under which the valve opens, and which shall be simple, effective and capable of being 40 locked in any desired position.

The means for carrying out the above objects will be more fully set forth in the following description which relates to the drawings and the essential characteristics of my invention will be summarized in the 45 claims.

In the drawings, Fig. 1 is a front elevation 50 of a player piano having the lower front panel removed and showing a part of the valve mechanism embodied in an expression device. Fig. 2 is a front elevation of the expression device having the cover removed 55 and showing part of the valve mechanism in

section; Fig. 3 is a vertical section taken on the line 3—3 in Fig. 2; Fig. 4 is a transverse section taken on the line 4—4 in Fig. 2; and Fig. 5 is a vertical section on an enlarged scale taken on the line 5—5 in Fig. 4. 60

In Fig. 1, I have shown a player piano as comprising a casing 10 having a roll box (not shown) in the upper part of the casing, and a motor-driven air pump 11 in the lower part of the casing. The pump exhausts air 65 from the wind chest 12, through conduits 13 and 14, while an expression device 16 operates through a conduit 15 to modify the air tension by admitting atmospheric air more or less freely through the conduit 13. This 70 device is automatically controlled from the note sheet through the medium of conduits 17, which are connected to independent openings in the tracker bar.

The expression device itself comprises, 75 briefly, a series of chambers 20, 21, 22, 23 and 24, which are separated by partitions 25, 26, 27 and 28, and a series of ports 29 and 30 which provide communication between such chambers. The chamber 20 is in communication with the atmosphere through a port 35, and the chamber 24 is in communication with the conduit 15 through a port 36. The flow through the ports 29 and the port 35 is restrained by yieldable valves 37, while the 80 flow through the remaining ports is controlled by positively actuated valves 41.

My invention is directly concerned with the yieldable valves, all of which are identical, and accordingly only one of those valves 90 will be described. Referring then to Fig. 5, each valve is shown as comprising a strip of flexible material 61 which is anchored on one end as at 52, to the under side of a partition; the other end being free to slide back 95 and forth as the valve is respectively opened and closed. Secured to the under side of the flexible strip, I have shown two members 50, and 51 which form a collapsible valve. The member 51 may be provided with a 100 longitudinal groove 54 in which the free end of an L-shaped spring 55 is adapted to rest; this spring being employed for holding the valve against the under surface of the partition whereby the associated port is 105 closed.

In the carrying out of the invention of the Swensen patent above mentioned, it is found that the spring closed patent valves 110 must each open a considerable distance, and

one or more must open under very light pressure, while the others must open a corresponding distance under very heavy pressure. The closing springs are limited as to 5 the size, owing to the fact that they must be within a comparatively small casing, wherefore it has been found necessary, to secure the best results, to use springs of different size. With the present invention, the deflection of the springs in proportion to the amount of valve opening is so slight, that the adjustments for the valves may be entirely taken care of by my adjusting mechanism, and the springs may be all the same 10 size and yet the best results be obtained. 15

This adjusting mechanism comprises a bent spring lever 55 fulcrumed at 56, with one end of the lever extending around an adjusting stem or rod 57. The end of the 20 rod adjacent the lever is threaded into a U-shaped nut 58, whereby the tension in the lever holds the end 59 against the nut, while the free end of the lever retains the valve against the corresponding valve seat. The 25 stem 57 extends through the wall of the expression box and is provided with a button 60 for turning it.

To prevent altering of the adjustment by unskilled persons, I provide a simple and effective locking means which is embodied in a screw 65, the head of which engages the flange 66 on the button 60. This lock may be effective by making the flange separate from the button in the form of a washer, in which case, the button and washer may be locked together by being threaded to the outer end of the stem 57.

The flexible strip 61 may be made of fabric impregnated with rubber, or of any suitable material which silences the operation of the valve and still possesses sufficient strength to withstand continuous bending, such as occurs on the lines where the members 50 and 51 are hinged, and where the member 50 is anchored.

In operation, whenever any of the positive valves are closed, then the restrained air acts directly against the hinge of the corresponding yieldable valve whereupon the valve is collapsed, the free edge 53 of the strip 61 sliding along the under surface of the partition. Similarly, the spring lever 55 slides along the groove 54, and in this way the valve may be operated without over-coining the full tension in the spring. When the valve closes, the sliding action between the partition and spring, prevents a sudden engagement between the valve and seat, and thus insures quietness, with sufficient rapidity, to obtain efficient operation.

From the foregoing description, it will

be seen that my invention may be readily attached to existing devices for overcoming objectionable features pertaining to the operation thereof. In addition, an expression device embodying my invention responds more readily than existing valves, and hence increases the degree of perfection with which 65 selections may be reproduced.

Having thus described my invention, I claim:

1. In combination, a casing, a member carried by the casing and having an opening therein, a valve hinged intermediately and disposed across the opening, there being a portion of the valve on each side of the hinge disposed opposite the opening, said valve having one end mounted stationary with reference to the member, and having the other end slidable on said member, a spring for normally holding said valve in closed position and means adjustable from a point outside the casing for varying the tension on said spring.

2. In combination, a casing, a partition wall carried by the casing for dividing it into a plurality of compartments, said partition having an opening therein, a valve hinged intermediately and having a portion thereof on each side of the hinge for normally closing said opening, a spring for urging the valve into closed position, said spring being pivoted intermediately, and means operable from a point outside the casing for moving the spring about the pivotal connection thereof to vary the tension with which the spring engages said valve. 85 90 95 100

3. In combination, a casing, a partition carried by the casing for dividing it into a plurality of compartments, said partition having an opening therein, a valve hinged intermediately and having a portion thereof on each side of the hinge disposed opposite the opening, said valve having one of the hinged portions rigidly mounted on the member and having the other hinged portion slidable on the partition, a spring bent intermediately and fulcrumed adjacent the bend, one end of said spring being in engagement with one of the hinged members for normally urging the valve into closed position, and the other end of said spring having a threaded engagement with said spring opening for swinging the spring about the fulcrum to vary the tension with which the valve is held against the seat, said threaded member extending outside the casing so as to permit adjustment of the spring from a point outside said casing.

In testimony whereof, I hereunto affix my ¹²⁰ signature.

CLINTON H. HANSON.
